(57) **CLAIM**

The ornamental design for a modular office partition, as shown and described.

DESCRIPTION

FIG. 1 is a perspective view embodying the inventive design;

FIG. 2 is a front view thereof;

FIG. 3 is a left view thereof;

FIG. 4 is a rear view thereof;

FIG. 5 is a top view thereof; and,

FIG. 6 is a bottom view thereof.

The broken lines are directed to portions of the modular office partition that form no part of the claimed design.

1 Claim, 5 Drawing Sheets
